UNITED STATES PATENT OFFICE.

JOHN D. TAYLOR, DECEASED, LATE OF WILKINSBURG, PENNSYLVANIA, BY MARY E. TAYLOR, EXECUTRIX, OF CHILLICOTHE, OHIO; SAID JOHN D. TAYLOR ASSIGNOR TO THE UNION SWITCH & SIGNAL COMPANY, OF SWISSVALE, PENNSYLVANIA, A CORPORATION OF PENNSYLVANIA.

HOLDING DEVICE.

1,170,360.

Specification of Letters Patent.

Patented Feb. 1, 1916.

Original application filed August 28, 1912, Serial No. 717,436. Divided and this application filed April 11, 1914. Serial No. 831,263.

To all whom it may concern:

Be it known that JOHN D. TAYLOR, deceased, formerly a citizen of the United States, residing at Wilkinsburg, in the 5 county of Allegheny and State of Pennsylvania, did invent certain new and useful Improvements in Holding Devices, of which the following is a specification.

The invention relates to holding devices.

One feature of the invention is the provision of a holding device whose action is due to induction.

The present application is a division of an application filed by the said John D. Taylor 15 on August 28, 1912, Serial No. 717,436, for railway signals.

Holding devices embodying the present invention are particularly well adapted for use in railway signals to hold the semaphore 20 against the action of gravity or other biasing force, although they are not limited to this particular adaptation.

One form of holding device embodying the invention will first be described and the 25 novel features thereof then pointed out in claims.

In the accompanying drawings, Figure 1 is a view showing in front elevation one 30 form of holding device embodying the invention. Fig. 2 is a sectional view on the planes indicated by line II—II in Fig. 1, looking in the direction of the arrows. Fig. 3 is a view on the plane indicated by the 35 line III—III in Fig. 1, looking in the direction of the arrows.

Similar reference characters refer to similar parts in each of the several views.

Referring first to Figs. 1 and 2, the device here shown comprises a stator or primary member 29, and a rotor or secondary member 48. The stator or primary member 29 comprises a plurality of laminations of transformer iron suitably clamped together between two end plates 29^a of similar material, and is formed with a plurality of inwardly projecting pole-pieces 50, here shown as being eight in number. This stator member is provided with a winding 31 comprising a coil on each pole-piece, 50 which winding 31 may at times be supplied with alternating current from a generator G, the circuit being controlled by a

contact 10 operated by any suitable means. The coils are so wound and connected that when the winding is energized, adjacent 55 pole-pieces 50 differ in polarity at any one instant.

The rotor or secondary member 48 comprises a plurality of rings of thin transformer iron having embedded therein a plurality of rods 52 of electro-conductive material, preferably copper, the number of rods preferably being equal to the number of pole-pieces 50. These rods are electrically connected by end rings 30 of electro-conductive material, also preferably of copper. It will be seen, therefore, that the rotor comprises a plurality of closed electric circuits and may therefore be termed a "squirrel-cage" rotor. The rods 52 are 60 fixed securely in the end rings 30 so that they serve also as rivets to clamp the laminations together. As here shown, the stator or primary member 29 is stationary, being fixed in an inclosing box 37, and the rotor or secondary member is carried by a spider 12 which is keyed to a spindle 15 suitably mounted to rotate in bearings 11 in the box 37, only one of which bearings is shown in the drawings. 65

It will be seen from the foregoing that the holding device is a transformer device having a fixed primary member 29 and a rotatable secondary member 48. 70

The spindle 15 may be connected with any movable member which it is desired should be held in one or more given positions against the action of a force tending to cause it to move. For example, the movable member may be a railway signal semaphore as shown in the application of John D. Taylor, Serial No. 717,436, of which the present application is a division. This is indicated diagrammatically in Fig. 2 of the 85 present drawings, in which S is a semaphore which is biased by gravity to the danger position and which may be moved to one or more other positions, such as caution and clear, by an electric motor M. In the construction here indicated, it is understood 90 that while the motor M is moving the semaphore away from the danger position the winding 31 is deenergized so that the holding device offers no opposition to this 95 100

movement, but that when the semaphore reaches the position in which it is to be held the motor M is deenergized and the winding 31 is energized by the closure of contact 5 10 shown in Fig. 1.

The holding action of the device is due to the fact that when the winding 31 is energized by alternating current the magnetic flux from the pole-pieces 50 flowing through the rotor 48 tends to hold the latter in such position that the rods 52 are opposite the middle points of the pole-pieces, because in this position no current is induced in the rods. Considerable force is required to 15 move the rotor from this position, and this force increases as the rods approach the edges of the pole-pieces. The parts are so adjusted and proportioned that the force acting on the semaphore S is less than the 20 force required to drag the rods 52 beyond the edges of the pole-pieces.

It is sometimes desirable that the stator member 29 be employed to control an armature which operates one or more circuit controlling contacts or other apparatus; this function may be accomplished in the following manner: A slot 51 is cut through the stator between two adjacent pole-pieces 50^a and 50^b, and a movable armature 46 is 25 mounted opposite the gap thus formed. This armature is of soft iron, and is preferably formed of a plurality of laminations held together by a clamp 44 which is riveted to a lever 45 pivotally mounted in trunnion screws 45^a in a box 39 attached to the box 37. The laminations of armature 46 are parallel with the plane of the paper in Fig. 1, and are obscured by the clamp 44 in Fig. 3, hence they are not shown in the drawings. Fixed 30 to the lever 45 by means of insulation studs 47 are two contact fingers 40 and 41, the former of which makes contact with a fixed block 42 when the armature is attracted to the stator, and the latter of which makes 35 contact with a fixed plate 43 when the armature falls away from the stator. The armature 46 is prevented from actual contact with stator 29 by a stud fixed in the end of lever 45, which stud engages with a stud 32 fixed 40 in box 37.

With the slot 51 in the stator, it is evident that the flux which otherwise would flow in the circuit including pole-pieces 50^a and 50^b and the portion of the stator joining these 45 pole-pieces, would now tend to flow from the base of one of these pole-pieces through almost the entire circumference of the stator to the base of the other pole-piece, and vice-versa, so that little or no flux would 50 flow through the armature 46. To prevent this, that is, to force some of this flux to flow through the armature 46, a low-resistance closed electric circuit is placed on each 55 pole-piece 50^a and 50^b, each of which circuits comprises two copper rods 53 passing

through the stator and electrically connected on each face of the stator by a copper plate 49. Each of these circuits is so placed that its plane is parallel to the normal direction of the magnetic flux in the pole-piece, hence 70 they do not interfere with the flux passing from these pole-pieces through the rotor 48. They do, however, force part of this flux to return through armature 46, and this flux causes the armature to be raised toward the 75 stator. This action of the closed circuits is due to the fact that the flux in the adjacent halves of pole-pieces 50^a and 50^b would, if 80 it were to return through the unbroken part of the stator, have to pass through the low-resistance circuits on these pole-pieces, but these circuits offer high impedance to the flux, hence this flux, or a portion of it, passes through the branch path including 85 armature 46.

Although there is herein shown only one form of holding device embodying the invention, it is understood that various changes and modifications may be made therein within the scope of the appended 90 claims without departing from the spirit and scope of the invention.

Having thus described the invention, what is claimed is:

1. A holding device comprising a stator, 95 a single phase winding for said stator, and a squirrel-cage rotor having the same number of rods as the stator has poles.

2. A holding device comprising a stator, 100 a single phase winding for said stator, and a rotor having the same number of closed electric circuits as the stator has poles.

3. A holding device comprising a stator, 105 a single phase winding for said stator, and a rotor with a short-circuited winding having the same number of poles as the stator.

4. A holding device comprising a stator having an energizing winding, a rotor, a gap in the stator, an armature adapted to bridge said gap, and means for causing part 110 of the magnetic flux in the stator to pass through said armature.

5. In combination, a substantially ring-shaped member of magnetizable material having pole-pieces and having a gap between two of said pole-pieces, windings on 115 said pole-pieces, an armature adapted to bridge said gap, and means associated with said ring-shaped member for causing part of the flux from the pole-pieces adjacent 120 said gap which would otherwise return through the unbroken portion of the member to flow through the armature.

6. In combination, a substantially ring-shaped member of magnetizable material 125 having pole-pieces and having a gap between two of said pole-pieces, windings on said pole-pieces, an armature adapted to bridge said gap, and a circuit of electro-conductive material on one of the pole-pieces 130

adjacent said gap, said circuit being so disposed that its plane is substantially parallel to normal direction of magnetic flux in the pole-piece, whereby a portion of the flux from said adjacent pole-piece which would otherwise return through the unbroken part of the member is caused to pass through said armature.

7. In combination, a substantially ring-shaped member of magnetizable material having pole-pieces and having a gap between two of said pole-pieces, windings on said pole-pieces, an armature adapted to bridge said gap, and a circuit of electro-conductive material on each of the pole-pieces adjacent said gap, each circuit comprising conductors extending through the stator and other con-

ductors connecting said conductors on each face of the stator, each circuit being so disposed that its plane is substantially parallel to the normal direction of magnetic flux in the pole-piece, whereby a portion of the flux from said adjacent pole-piece which would otherwise return through the unbroken part of the member is caused to pass through said armature.

In testimony whereof I affix my signature in presence of two witnesses.

MARY E. TAYLOR,
*Executrix of the estate of John D. Taylor,
deceased.*
